UNITED STATES PATENT OFFICE.

JOHN F. DODGE AND HORACE E. DODGE, OF DETROIT, MICHIGAN, ASSIGNEES TO DODGE BROTHERS, OF DETROIT, MICHIGAN, A CORPORATION OF MICHIGAN.

DESIGN FOR A CAR-BODY.

46,565.

Specification for Design.

Patented Oct. 20, 1914.

Application filed August 11, 1914. Serial No. 856,311. Term of patent 7 years.

To all whom it may concern:

Be it known that we, JOHN F. DODGE and HORACE E. DODGE, citizens of the United States, residing at Detroit, Michigan, have invented a new, original, and ornamental Design for Car-Bodies, of which the following is a clear, full, and exact description.

Referring to the accompanying drawings forming a part thereof, Figure 1 is a plan view of our design; Fig. 2 a side elevation thereof; and Fig. 3 a front elevation. Fig. 4 a rear elevation.

What we claim is:

The ornamental design for a car body, substantially as shown in the accompanying drawing.

Signed at Detroit, Michigan, this 30th day of July, 1914.

JOHN F. DODGE.
HORACE E. DODGE.
